UNITED STATES PATENT OFFICE

AUBREY DELOS TURNER, OF MINNEAPOLIS, MINNESOTA

CLAMP

Application filed December 3, 1928. Serial No. 323,365.

This invention relates to a clamp, especially designed for use in connection with construction work, and aims to provide novel means whereby uprights or cross bars of scaffolds, or other building apparatus may be securely clamped together in the formation of portable supports or scaffolds.

An important object of the invention is to provide a clamp of this character embodying a wedge shaped member adapted to be forced between a movable end bar of the clamp, and an article being clamped by the device, so that the clamp may be positioned without the use of nails, screws, or other securing means.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a view illustrating bars of construction work secured together by means of a clamp constructed in accordance with the invention.

Figure 2 is a sectional view taken on line 2-2 of Figure 1.

Figure 3 is a view of the clamp ready to be positioned.

Referring to the drawing in detail, the clamp embodies end members 5 and 6 respectively, the end member 6 being provided with teeth 7 to bite into the bars or bar to which the device is secured, to insure against the clamp slipping when positioned.

Pivotedly connected with the end bar 6, at a point adjacent to each end thereof, is a pair of bars 8 and 9 respectively, the bars 8 being pivotedly connected with the end bar 5, at 10, so that the bar 5 will swing between the bars 8.

The bars 9 are connected at their ends by means of the pin 11', and are held in spaced relation with each other by the spacing block 11, defining a clearance for the wedge 12 that

is positioned therebetween, there being provided pins 13 on the wedge 12 to restrict movement of the wedge and insure against the wedge becoming disconnected from the bars 9.

Formed in the upper edge of the bar 5 is a notch 14 that is adapted to engage the pin 11', at a point between the bars 9 to hold the side bars against spreading when the wedge is being positioned.

In the use of the device, the clamp is opened in a manner as shown by Figure 3, whereupon the bars to be connected are placed side by side as shown by Figure 1. The clamp is now positioned in such a way as to grip the overlapping ends of the bars to be connected and the bar 5 is moved to a position between the bars 9.

The wedge 12 is now driven into position behind the bar 5, with the result that the bars being connected, and which are indicated by the reference character A, are forced into close engagement with each other and securely held in such a way that the use of nails and screws is unnecessary.

Should it be desired to release the clamp, the wedge may be struck from the pointed end moving the wedge in the opposite direction permitting the clamp to open.

I claim:

1. A clamp of the class described including an end bar, pairs of side bars pivotally connected with the end bar and arranged on opposite sides thereof, a pivoted end bar mounted between the pair of side bars at one side of the clamp, a pin for connecting the opposite pair of side bars at the free ends thereof, said pivoted end bar adapted to pass under the pin, and a wedge shaped member slidably mounted between the second mentioned pair of side bars and engaging the pivoted end bar for forcing the pivoted end bar into close engagement with the pin to lock the clamp in its closed position.

2. A clamp of the class described including an end bar, pairs of side bars pivotally connected to the end bar, a swinging end bar held between one pair of side bars and adapted to swing between the bars of the opposite pair, latching means for latching the free

end of the last mentioned bar, and a wedge contacting with the swinging bar and articles being connected by the clamp to hold the swinging end member against movement.

5 In testimony that I claim the foregoing as my own, I have hereto affixed my signature.

AUBREY DELOS TURNER.
